US00D709878S

(12) **United States Design Patent**
Akana et al.

(10) **Patent No.:** US D709,878 S
(45) **Date of Patent:** ** Jul. 29, 2014

(54) **DISPLAY**

(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Laura Michelle Deforest**, San Mateo, CA (US); **Danielle De Iulius**, San Francisco, CA (US); **Adam Terence Garelli**, San Jose, CA (US); **Joss Giddings**, San Francisco, CA (US); **Bradley Joseph Hamel**, Redwood City, CA (US); **M. Evans Hankey**, San Francisco, CA (US); **Keith Hendren**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Dinesh Cherian Mathew**, San Francisco, CA (US); **Bryan William Posner**, La Selva Beach, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/424,266**

(22) Filed: **Jun. 9, 2012**

(51) LOC (10) Cl. **14-02**

(52) U.S. Cl.

USPC **D14/371; D14/374**

(58) **Field of Classification Search**

USPC ..... **D14/315-327, 439, 371, 374, 375, D14/125-129; D18/1, 2, 7, 11; 235/145 A, 235/145 R; 341/22, 23; 345/104, 156, 168, 345/169, 173; 361/679.08, 679.09, 679.11, 361/679.26, 679.27; 16/367**

(57) **CLAIM**

The ornamental design for a display, as shown and described.

DESCRIPTION

FIG. 1 is a top perspective view of a first embodiment of a display showing our new design;

FIG. 2 is a bottom perspective view thereof;

FIG. 3 is top view thereof;

FIG. 4 is a bottom view thereof;

FIG. 5 is a front view thereof;

FIG. 6 is a rear view thereof;

FIG. 7 is a left view thereof;

FIG. 8 is a right view thereof;

FIG. 9 is a top perspective view of a second embodiment thereof;

FIG. 10 is a bottom perspective view thereof;

FIG. 11 is top view thereof;

FIG. 12 is a bottom view thereof;

FIG. 13 is a front view thereof;

FIG. 14 is a rear view thereof;

FIG. 15 is a left view thereof; and,

FIG. 16 is a right view thereof.

The broken lines are for the purpose of illustrating portions of the electronic device and form no part of the claimed design. The light shade lines on the surface portions indicate contour and not surface decoration.

1 Claim, 12 Drawing Sheets
